COVERED RECEPTACLE TRAY FOR COMB
AND BRUSH SETS OR SIMILAR ARTICLES

Charles Castelli, Union City, N. J., assignor to Columbia Protektosite Co. Inc., Carlstadt, N. J., a corporation of New Jersey

Application June 16, 1949, Serial No. 3,307

Term of patent 7 years

(Cl. D86—10)

To all whom it may concern:

Be it known that I, Charles Castelli, a citizen of the United States and resident of Union City, in the county of Hudson, State of New Jersey, have invented a new, original, and ornamental Design for Covered Receptacle Tray for Comb and Brush Sets or Similar Articles, of which the following is a specification, reference being had to the accompanying drawing, forming a part thereof, and of which

Fig. 1 is a perspective view of a receptacle tray for comb and brush sets, of my new design showing the cover removed from the base tray.

Fig. 2 is a bottom perspective view of the base tray, and

Fig. 3 is a perspective view, on a smaller scale, showing the cover in its normal position on the base.

I claim:

The ornamental design for a covered receptacle tray for comb and brush sets or similar articles, substantially as shown.

CHARLES CASTELLI.
